UNITED STATES PATENT OFFICE.

JOHN HOPSON, JR., OF NEW LONDON, ASSIGNOR TO THE WATERBURY CLOCK COMPANY, OF WATERBURY, CONNECTICUT.

DESIGN FOR A CLOCK-CASE.

SPECIFICATION forming part of Design No. 23,698, dated October 16, 1894.

Application filed September 7, 1894. Serial No. 522,400. Term of patent 7 years.

To all whom it may concern:

Be it known that I, JOHN HOPSON, Jr., of New London, in the county of New London and State of Connecticut, have invented a new 5 Design for Clock-Cases; and I do hereby declare the following, when taken in connection with the accompanying drawings and the letters of reference marked thereon, to be a full, clear, and exact description of the same, and 10 which said drawings constitute part of this specification, and represent, in—

Figure 1, a view in front elevation of a clock case embodying my design; Fig. 2, a side view thereof; Fig. 3, a plan view of the case.

15 My invention relates to a design for clock cases, and consists in the configuration and ornamentation as hereinafter described and shown in the accompanying illustrations.

20 My clock-case is tapering in general form, and has at its corners heavy inclined ribs A, which project beyond the planes of its front and sides, and which are more or less broken with ornaments. The front of the clock-case has a dial-opening B, below which are located 25 two panels C, formed by beads or pearls arranged in line and inclosing small flower-like

figures c. Between these panels I locate a rose-like figure D and a large arabesque D'. Above the dial-opening I locate a flamboyant scroll E, having long leaf-like extensions E', 30 which extend down over the upper edges of the ribs A which flank the front of the case. From these scrolls E' depend sprays E² of flowers. Each side of the case contains an oblong panel F, formed by lines of beads or 35 pearls, and containing small flower-like bosses F'. Below this panel is an arabesque G, while above it is a highly ornate arabesque G'. The extreme top of the case is formed by a rectangular block H, having a rounded surface 40 and ornamented with small flowers H' and fleur-de-lis H².

I claim—

The design for a clock case, substantially as herein shown and described.

45 In testimony whereof I have signed this specification in the presence of two subscribing witnesses.

JOHN HOPSON, JR.
